UNITED STATES PATENT OFFICE.

DAN B. SWICKARD, OF GALVA, ILLINOIS.

PLIERS.

1,345,035.

Specification of Letters Patent. Patented June 29, 1920.

Application filed July 25, 1919. Serial No. 313,365.

To all whom it may concern:

Be it known that I, DAN B. SWICKARD, citizen of the United States, residing at Galva, in the county of Henry and State of Illinois, have invented certain new and useful Improvements in Pliers; and I do hereby declare that the following is a full, clear, and exact description of the invention, which will enable others skilled in the art to which it appertains to make and use the same.

This invention relates to improvements in pliers.

The object of the invention is to improve 15 on the construction of pliers as ordinarily produced, simplifying the same and rendering it stronger, besides reducing the cost of manufacture.

Another and important object, however, 20 is to improve upon and simplify the construction of the pliers forming the subject of my pending application for Patent No. 282,182, filed March 12, 1919 as will appear more fully herein aided by the accompanying drawing which forms part of this 25 application, in which,

Figure 1 is a plan of my improved pliers, and

Fig. 2 is a front elevation of the same. 30 The pliers comprises, first, a jaw 1 and a handle portion 2 having the general form of an irregular curve after the manner of plier construction, and, secondly, it has a companion jaw 3 and a handle portion 4, said jaw 3 having near its fulcrum a notch 5 to receive a wire, nail or other object to be cut, the said jaw 1 acting therewith to sever such object.

Said jaw 3 has an ear 6 extending from 40 its outer edge. 7 is a thread-bar having one end pivoted to the ear by means of a rivet 8, its other end, which is free, extending through a loop 9 extending from said handle portion 2, as shown, said thread-bar 45 being slidable within said loop in the pivotal action of the jaws. 10 is a nut adapted for adjustment upon the thread-bar as described in my pending application referred to.

50 11 indicates a pair of links, one lying at each side of the pliers as clearly shown in Fig. 2, it being observed that the jaws are reduced in thickness near the handle portions as indicated at 12 so that said links 55 may be permitted to lie flat upon said jaws and to be parallel to one another.

The rivet 8 serves to pivotally connect the said thread-bar 7 and the ear 6, as explained, besides pivotally connecting said links 11 to said ear.

The opposite ends of the links receive a rivet 13 which extends through both jaws, the jaw 1 having a snug working fit thereon, while the jaw 3 has an arcuate slot shown in broken lines at 14, which is described from the center of the rivet 8, the rivet 13 swinging therein.

The links 11 support the jaw 1 and rivet 13 and guides the same throughout the slot, it being seen that as the said jaw and rivet 70 can move about the rivet 8 through the links, the jaw 3 likewise moves about that rivet producing a smooth acting tool.

My pliers thus constructed are exceedingly strong and rigid from the fact that 75 the ear 6 is an integral part of the jaw 3, being forged in one piece with the latter. By this means the thread-bar, when pressure or great strain is placed thereon in, or during certain operations, as in holding or 80 turning a nut, or when the pliers are used as a pipe wrench, will have a very solid and firm connection that cannot become bent or twisted under extreme and repeated forces.

Moreover, by having straight links, as 85 11 described, such links are not subjected to strains likely to bend them or tend to buckle them.

Again, by pivoting the links to the ear 6 at the outer side of the jaw said links are removed from the work-engaging faces of the jaws so as not to interfere with any operations. The jaws are, therefore, entirely free while at the same time ready to act in any 90 capacity with perfect freedom.

The tool is thus thoroughly simplified in construction and reduced in cost of production.

Having thus described my invention, I 100 claim:

1. A pliers including its jaws pivotally connected, one of said jaws having an ear extending from its outer edge, a link pivot- 105 ed at one end to said ear and at its other end at the pivot of the jaws, a looped portion extending from the handle portion of one of the jaws, a thread-bar pivoted to said ear and slid able within said portion, and a member adjustable upon the thread- 110 bar between the ear and said portion.

2. A pliers including its jaws pivotally connected, one of said jaws having an ear

extending from its outer edge, a link pivoted at one end to said ear and at its other end at the pivot of the jaws, a looped portion extending from the handle portion of the opposite jaw, a thread-bar pivoted to said ear and slidable within the said portion, and a member adjustable upon the thread-bar, there being a slot in one of the jaws describing an arc from the pivot of the said link.

3. A pliers including its jaws pivotally connected, one of said jaws having an ear extending from its outer edge, links pivoted at one end at side of the ear, and each pivoted at their other ends to the pivot member

of the jaws, a looped portion extending from the handle portion of the opposite jaw, a thread-bar pivoted to said ear and slidable within the said portion, and a member adjustable upon the thread-bar, there being an arcuate slot in one of the jaws at its pivot point described from the pivot of the links at said ear.

In testimony whereof I affix my signature in presence of two witnesses.

DAN B. SWICKARD.

Witnesses:

FRED A. CARLSON,
J. L. LOVGREN.
